HOCKEY GAME BOARD

Pierre Delfausse, Crown Hill, Madison, N.J. 07940

Filed Sept. 17, 1968, Ser. No. 13,560

Term of patent 14 years

Int. Cl. D21—01

U.S. Cl. D34—5

The board is of conventional thickness. The figure is a plan view of a hockey game board showing my new design. Conventional numerals are shown in broken lines.

I claim:

The ornamental design for a hockey game board, as shown and described.
